UNITED STATES PATENT OFFICE.

FREDERIC E. KIP, OF MONTCLAIR, NEW JERSEY.

DESIGN FOR PILE FABRIC.

No. 37,509.

Specification for Design.

Patented Aug. 8, 1905.

Application filed May 20, 1905. Serial No. 261,463. Term of patent 14 years.

To all whom it may concern:

Be it known that I, FREDERIC E. KIP, a citizen of the United States, and a resident of Montclair, in the county of Essex and State of New Jersey, have invented a new, original, and ornamental Design for Pile Fabrics.

The design is illustrated in the accompanying drawing, which shows in plan or face view the complete new design.

I claim—

The ornamental design for a pile fabric as shown.

FREDERIC E. KIP.
